UNITED STATES PATENT OFFICE.

ALBERT R. KUNKEL, OF SAN ANTONIO, TEXAS.

BURNER.

1,385,875.

Specification of Letters Patent. Patented July 26, 1921.

Application filed August 17, 1920. Serial No. 404,196.

To all whom it may concern:

Be it known that I, ALBERT R. KUNKEL, a citizen of the United States, and residing at San Antonio, Bexar county, State of 5 Texas, have invented certain new and useful Improvements in Burners, of which the following is a specification.

This invention relates to oil burners used for heating purposes and consists in an improvement on the burner construction disclosed and claimed in my Patent No. 1,184,185, granted May 23, 1916. One of its principal purposes and functions is to secure more perfect combustion of the gaseous mixture escaping from the gas jets and to prevent condensation of the vaporous oil in said mixture. One of its main features resides in flat tapering air tubes leading up through the drip pan on opposite sides of the burner 10 pipe and so curved toward and over said pipe as to discharge substantially directly across and close to the upwardly directed jets of combustible gases issuing from said burner pipe. The air tubes are arranged in 15 pairs with their discharge ends close together parallel and horizontal, facing each other and the gas jet passes up between their discharge ends about midway of their length. I find that this arrangement, particularly with a burner construction such as disclosed in my Patent No. 1,184,185 supplies the right amount of air in the right way to produce perfect combustion, thus securing the beneficial effect of all of the heat 20 units in the fuel and avoiding condensation and the dripping of oil from the burner pipe. It will be noted that the rate of flow of air through the air tubes to support combustion is largely caused by the draft or suction produced by the jet of burning gas passing directly across the discharge ends of the tubes and that the supply of air to the gas jets is thus automatically varied with the demand. The novel features of the invention will be more fully appreciated from the following description taken in connection with the drawings.

In the drawings:

Figure 1 is a plan view looking down on one form of burner embodying my invention; and

Fig. 2 is a cross section on the line 2—2 of Fig. 1 but showing the flame deflector on the upper generating pipe in full lines.

As fully explained in my patent above mentioned, a proper mixture of oil and air is supplied under pressure to the gas generating or heating pipe 10 from suitable sources through the regulating valve 11. In pipe 10 the mixture is highly heated by the combustion of gases directed toward it from below as hereinafter described, and is converted into proper combustible gaseous form. It is then conveyed downwardly at 12, after passing through the heating zone, to one end of the burner pipe 13 which is below and parallel to pipe 10 and which has at suitable intervals gas discharge orifices 14 directed upwardly toward pipe 10. The burner pipe 13 has connected to its other end a gas retainer or pressure pipe 15 which is imperforate parallel to the burner pipe and, as will be seen by reference to Fig. 1, the elbow joint 16 forms the connection. The pipe or gas retainer 15 serves to receive any excess gas generated at any time and to hold it under pressure ready to be discharged from the burner openings, thus compensating for any irregularities in the action of the generator and insuring a substantially uniform gas discharge from the burner openings. Flame distributors and heat absorbers 17 of metal are suspended from pipe 10 by any suitable means such as ring-shaped loops 18 and are placed directly above the gas jet 85 openings 14 so that the jets of burning gases will strike them centrally under the bottom and be properly spread and the heat distributed instead of striking the pipe 10 directly and possibly overheating it locally.

The burner is provided with a drip pan below the burner pipe 13 preferably made of pressed galvanized iron and it has a horizontal top portion 20 and the vertical downwardly extending side portions or flanges 21 at the margins of the top portion. In the upper surface 20 of the drip pan there is a central longitudinal depression 22 directly below the burner pipe 13 but terminating short of the ends of the portion 20. That depression constitutes an oil receptacle or groove and is partially filled with asbestos

23. This arrangement is particularly useful in starting the operation of the burner since the oil may be turned on even when the device is cold and allowed to pass out through 5 the burner openings 14 and to fall in the depression 22 saturating the asbestos and may be then ignited and burned to heat the oil in the generator pipe 10 and connections sufficiently to form the combustible gaseous mixture. It thus acts effectively as a primary 10 heater for the burner. The drip pan is connected to the burner pipe 13 by a galvanized iron clamp 24 secured to the top portion 20 of the drip pan by screws 25 on opposite 15 sides of the center portion 26, being bent in the arc of a circle up over pipe 13 and one end 27 extending beyond the edge of the drip pan and being bent down over the gas retainer pipe 15. The parts are thus securely fastened in position.

20 As set forth in my prior Patent 1,184,185, the drip pan together with the burner mechanism which it carries, is adapted to be placed on the ordinary grate of a stove and the drip pan of course cuts off a free 25 and open supply of air up through the grate to the burner. In my prior patent I made use of elongated slots in the top of the drip pan to supply the necessary air for combustion properly and in the right quantity, but 30 I have discovered that the results may be much improved by the use of my present improved means for conveying the air up through the drip pan to the discharge openings of the burner. According to my present invention the top 20 of the drip pan is 35 provided opposite each burner opening 14 with a pair of longitudinally extending parallel slots 28 and 29 on opposite sides of the groove or depression 22 and open ended air 40 supply tubes 30 and 31 are secured to the top portion 20 over and around the slots and extending upwardly therefrom. The tubes are rectangular in cross section and at 45 the point of connection to the top portion 20 their interior is in cross section the same shape and size as the slots 28 and 29, but from that point upward they taper transversely to the discharge ends at the top, as shown in Fig. 2. The tubes may be secured to the top 50 portion 20 in any suitable way and for this purpose flanges fitting the portion 20 may be formed on them. While the lower ends of the tubes are removed laterally a considerable distance from the burner pipe 13, 55 they are bent or curved from that point upwardly toward that pipe so that their upper discharge ends 32 and 33 are close together facing each other above pipe 13 with the gas discharge opening 14 directed upwardly 60 midway between them and midway of their length. Since they are so close together the jet of gas issuing from opening 14 passing across and between the outlet ends 32, 33 will act by suction to draw the 65 required amount of air from the tubes to

cause perfect and complete combustion of the gases. The suction being localized is much more effective in securing the right amount of air exactly where needed than was the slot arrangement of my prior patent 70 since in that case the suction was not as great and all of the air drawn in did not necessarily reach the desired point of use. I find that the air supply openings immediately adjacent and on both sides of the gas 75 jet and extending longitudinally on both sides of that jet supplying what may be called sheets of air serve to cause perfect combustion and avoid any condensation of the oil issuing from the discharge opening 80 14 after the burner is in operation.

It will be understood that any number of gas jet openings 14 may be used as desired or as is necessary in the particular device in which my invention is used, but in each 85 instance there should be the two air supply pipes as illustrated in Fig. 2. In Fig. 1 I have shown a structure in which there are two gas discharge openings. It will further be understood that my invention is not limited in its use to the particular form of burner arrangement shown, but as will be evident to those skilled in the art is applicable to various forms.

Having thus described the invention what is claimed as new and desired to be secured by Letters Patent is:

1. In an oil burner the combination with a gas generating portion, of a burner pipe below and connected thereto provided with an upwardly directed discharge opening, a drip pan secured in place and extending horizontally below said burner pipe and having therein a pair of elongated air passages one on each side of the burner pipe opposite the discharge opening and flattened air tubes extending upwardly from said passages to a higher level than the burner pipe and curved toward each other at their upper ends so as to discharge sheets of air 100 from opposite sides directly across the jet 105 issuing from said burner opening.

2. In an oil burner the combination with a gas generating portion, of a burner pipe below and connected thereto provided with an upwardly directed discharge opening, a drip pan secured in place and extending horizontally below said burner pipe and having therein a pair of parallel slots spaced from the sides of the burner pipe opposite the discharge opening and flat tapering tubes extending upwardly from said slots and curved toward each other over the burner pipe whereby their ends having slot-like discharge outlets will be directed toward each other close together on adjacent 115 120 opposite sides of the jet issuing from the burner opening.

3. In an oil burner, the combination of a device having spaced branches one of which is disposed above the other, the lower branch 130

having perforations therein facing the upper branch, a drip pan having a longitudinally extending oil groove disposed below said lower branch and adapted to catch oil from said perforations, a pair of slots for each perforation extending longitudinally of the groove on opposite sides and a pair of flat tapering air supply tubes for each

pair of slots extending upwardly from the drip pan and curved toward each other over 10 the pipe having the perforation and terminating in slot-like discharges facing each other immediately adjacent the line of movement of the jet of gas from said perforation.

In testimony whereof I affix my signature. 15

ALBERT R. KUNKEL.
